ABSTRACT: A circuit interrupter comprises a trip plate including a stop for limiting the stroke of a movable contact arm.

Upon an excessive current flow the interrupter a bimetal and/or an electromagnet causes the trip plate to be moved in such a direction that the movable contact is separated from the stationary contact by a distance greater than that provided by the normal opening operation.

PATENTED AUG 10 1971

FIG1

CIRCUIT INTERRUPTER

This invention relates to improvements in a circuit interrupter.

In order to effectively interrupt the overload or short-circuiting current flowing through circuit interrupters, it is desirable to provide a relatively great distance between a pair of separated contacts involved. This measure is objectionable in the case where the interrupters have to be manually operated. This is because making the distance between the separated contacts greater leads to difficulties in design and construction and the durability decreases.

Accordingly, an object of the invention is to provide a circuit breaker capable of changing the separation distance between the contacts from a small magnitude for manual opening operation to a large magnitude for automatic opening operation and wherein there is provided an improved mechanism by which the operation is rapidly and smoothly performed.

The invention accomplishes this object by the provision of a circuit interrupter comprising in combination, a pair of relatively movable contacts, an arm having disposed thereon one of said contacts, a switching mechanism coupled to said movable contact arm for driving said movable contact from its closed position to its open position and vice versa, a trip plate operative to automatically release said movable contact arm to separate said movable contact away from the other contact and a stop disposed on said trip plate to limit the separation movement of said movable contact arm from the other contact, the arrangement being such that upon automatically releasing the movable contact arm, said stopper is moved in a direction to increase the spacing between said pair of contacts as compared with the spacing between the contacts provided through the manual operation of the operating mechanism.

The invention will become more readily apparent from the following description taken in conjunction with the accompanying drawing in which:

FIG. 1 is a side elevational view partly in section of a circuit interrupter in its closed position constructed in accordance with the teachings of the invention; and

FIG. 2 is a schematic side elevational view of one portion of the circuit interrupter illustrated in FIG. 1 useful in explaining the operation of the invention.

While the invention will be shown and described in conjunction with a circuit interrupter of the three pole type, it is to be understood that the same is equally applicable to circuit interrupters of the single pole type and other multiple pole types. Also it is to be understood that the components common to all the poles will be described in terms of the central pole alone.

Referring now to the drawings and more particularly to FIG. 1, there is illustrated a three-pole circuit interrupter constructed in accordance with the teachings of the invention. The arrangement illustrated comprises a base member 2 and a detachable cover member 4 forming a closed enclosure. Both the members may be conveniently made of any suitable electrically insulating plastic by a moulding technique. Disposed at the bottom of the enclosure is a stationary contact 6 connected by way of an electric conductor 8 to a source terminal 10. A movable contact arm 12 of any suitable electrically conductive material is provided at that end facing the stationary contact 6 with a movable contact 14 and is rotatably secured by a pin 16 to a contact holder 18 pivotally mounted on an electrically insulating shaft 20 common to all the poles. The movable contact arm 12 is always biased toward the stationary contact 6 by the action of a spring 21 disposed around the pin 16 and is connected to a connector 22 through a flexible conductor 24.

In order to move the movable contact arm 12 from its closed position as illustrated in FIG. 1 to its open position as illustrated at solid line in FIG. 2 and vice versa, an operating mechanism generally designated by the reference numeral 26 is provided including an operating handle 28, an operating lever 30, operating springs 32 and a trip plate 34. The operat-

ing handle 28 is made of any suitable electrically insulating material and is fixedly mounted on one end of the operating lever 30 with the other end portion projecting beyond the cover member 4. The operating lever 30 is of an inverted U-shape section and is pivotably mounted at the other end on a pin 36 secured to a stationary frame 38. The operating springs 32 are anchored at one end to the one end portion of the lever 30 and are rotatably mounted on a toggle shaft 40. The trip plate 34 is in the form of a bell crank including one arm

5 pivotably mounted on the frame 38 by a pivot pin 42. When the movable contact arm 12 is in its manually open position as will be described hereinafter the trip plate 34 is adapted to be contacted at the free end 34a by the contact arm 12 thereby to prevent the arm from effecting a further movement in a direction to separate the movable contact 14 from the stationary contact 6. The trip plate 34 is further provided on the middle portion with a toggle pin 44.

10 A toggle link 46 is pivotably mounted at one end on the toggle pin 44 and articulated at the other end to another toggle link 48 by the toggle shaft 40. The toggle link 48 has its free end connected to the pin 16 along with the contact holder 18 and movable contact arm 12.

15 As shown in FIG. 1, the trip plate 34 normally engages a trip hook 50. More specifically, the trip hook 50 is rotatably supported on the stationary frame 38 by a pin 52 secured to the latter and includes a flat section generally upwardly directed and is provided on the upper end portion with a slot 54 which, in turn, normally engages the free end 34b of the other arm of

30 the trip plate 34.

20 A trip shaft 56 common to all the poles is rotatably supported by the stationary frame 38 and adjacent the trip hook 50. The shaft has fixedly secured thereon a protrusion 58 normally engaging the trip hook 50, under the action of a spring 35 60 disposed around the pin 52. The shaft 56 has further fixed thereon one trip piece 62 for each pole.

25 The arrangement further comprises an electromagnetically and thermally responsive device generally designated by the reference numeral 64. The device 64 includes a stationary electromagnet 66 having a cylindrical portion 66a around which a conductor 68 is wound. The conductor 68 has one end connected to the flexible conductor 24 through the connector 22 and the other end connected to one end of heater 70. The heater 70 has the other end connected to a conductor 45 72 connected to a load terminal 74. An L-shaped bimetal element 76 is disposed in close proximity to the heater 70 by having the lower shorter leg of the "L" mechanically connected to the adjacent portion of the heater 70 and there is controllably screw threaded into the upper end of the other leg an adjusting screw 78 facing both the free end of the trip piece 62 and one end of a movable iron piece 80. The movable iron piece 80 is rotatably secured at a point intermediate the two ends to the stationary frame 38 by a pin 82 and has the other end portion opposed to the stationary electromagnet 66. A spring 84 engages the pin 82 to normally maintain the movable iron piece 80 spaced away from the electromagnet 66. Under these circumstance, the one end of the iron piece 80 is slightly spaced away from the end of the adjusting screw 78.

30 Further an arc-extinguishing space 86 having a conventional construction is disposed in the region of the movable contact arm 14 as shown in FIG. 1.

35 In order to manually move the interrupter from its closed position as illustrated in FIG. 1 to its open position, the operating handle 28 can be turned to the OFF side or in the right-hand direction as viewed in FIG. 1. This turning movement of the operating handle 28 causes the pair of toggle links 46 and 48 to be folded into a V-shape due to the reversal of the line of action of the operating springs 32 which pull up the pin 16 on the movable contact arm 12. Therefore the movable contact arm 12 is rotated about the axis of the shaft 20 in the clockwise direction as viewed in FIG. 1 until it abuts against the lower end 34a of the trip plate 34 whereupon the arm is stopped at its position as shown at solid line in FIG. 2, resulting in the completion of the particular manual opening opera-

tion. As shown in FIG. 2, the movable contact 14 is maintained spaced away from the surface of the stationary contact 6 by a minimum distance "L₁." It is easily understood that a manual closing operation can be accomplished by turning the operating handle 28 in the left-hand direction as viewed in FIG. 1.

Upon the occurrence of a flow of overload current through the interrupter in its closed position, the bimetal element 76 is excessively heated and is deflected so that the free end thereof pushes the trip piece 62. This causes the trip shaft 56 and therefore its protrusion 58 to be rotated in the counterclockwise direction as viewed in FIG. 1 against the action of the spring 60 until the protrusion falls into the slot 54 on the trip hook 50. At that time the end 34b of the trip plate 34 disengages from the trip hook 50 to permit that plate to be rotated in a counterclockwise direction by the action of the operating spring 32 through the toggle link 46. This rotational movement of the trip plate 34 causes the toggle links 46 and 48 to collapse resulting from the reversal of the line of action of the spring 32 thereby to pull up the contact holder until the interrupter is in its open position.

If an excessive current whose magnitude may be on the order of 5 to 10 times the rating current flows through interrupter in its closed position then the movable iron piece 80 is attracted by the energized electromagnet so as to be rotated about the axis of the pin 82 in the counterclockwise direction and against the action of the spring 84 until it pushes the trip piece 62. Thereafter the process as above described is carried out to separate the movable contact 14 from the stationary contact 6.

After the tripping operation has been performed the movable contact arm 12 is located at the position as shown by dot-and-dash lines in FIG. 2. It is to be noted that with the tripping operation the movable contact 12 has been separated from the surface of the stationary contact 6 by a maximum distance L₂ greater than the minimum distance of L₁ obtained with the manual opening for the following reason:

As clearly shown by dot-and-dash lines in FIG. 2, the counterclockwise rotation of the tripping plate 34 results also in the upward movement of the protrusion 34a. Therefore, the movable contact arm 12 is permitted to be additionally moved beyond its open position provided by the manual opening operation until it abuts against the upwardly moved protrusion 34a for stopping. Thus the separation between the movable and stationary contacts is greater in the tripping operation than in the manual opening operation.

In summary, the operating handle 28 is manually operated

to separate the movable contact 14 from the stationary contact 6 a relatively small distance L₁. In a tripping operation due to the occurrence of a flow of over load or shortcircuiting current, the lower end of the bellcrank-shaped trip plate 34 is moved to permit the movable contact 14 to be moved away from the stationary contact 6 a distance greater than that obtained in the manual operation of the handle 28. Therefore the invention is advantageous in that for the normal switching operation, damage to the flexible conductor 24 and chattering of the movable contact arm 12 greatly decreases leading to an increase in durability because a relatively small separation distance permits the reasonable construction of circuit interrupters. At the same time, a relatively long separation distance obtained in a tripping operation or an automatic interrupting operation which results in an increase in interrupting capability.

While the invention has been illustrated and described in conjunction with a single preferred embodiment thereof it is to be understood that various changes and modification in the details of construction and the combination and arrangement of parts may be resorted to without departing from the spirit and scope of the invention. Instead of the stationary contact 6, a movable or semimovable contact may be used, if desired.

What we claim is:

- 25 1. A circuit interrupter comprising in combination a pair of relatively movable contacts, a movable contact arm having disposed thereon one of said contacts, a switching mechanism coupled to said movable contact arm for driving said movable contact from a closed position to an open position and vice versa, a trip plate pivotally mounted on said switching mechanism, a pair of foldable toggle links pivotably coupled at one end to the contact arm and at the other end to said trip plate, said trip plate normally being held in a first position and operative to be pivoted to a second position to actuate said toggle links and automatically actuate said switching mechanism to move said movable contact arm to separate said movable contact from the other contact upon flow of an excessive current, and a stop on said trip plate adjacent the pivotal mounting of said trip plate to limit the movement of said movable contact arm away from the other contact, the stop being in a position when the trip plate is in the second position which increases the distance the movable contact moves away from the other contact as compared with the distance the movable contact arm can move with the trip plate in said first position so as to increase the spacing between the contacts upon automatic operation as compared with manual operation.
